SPINNING RING AND TRAVELER THEREFOR

Harvey E. Herr, Buffalo, N. Y., assignor to Herr
Manufacturing Company, Inc., Buffalo, N. Y.,
a corporation of New York

Application August 24, 1938, Serial No. 226,499

7 Claims. (Cl. 57—120)

This invention relates to certain new and useful improvements in the spinning rings and travelers employed in connection with spinning machines.

5 It has for its chief object to provide a ring and traveler of this character which are designed to maintain an even and constant thread tension and wherein a downward and outward thrust or pressure of the traveler against the ring is provided to counteract any tendency of the thread to exert an upward pull on the traveler during the spinning operation and wherein the ring is provided with simple and effective means for lubricating the traveler.

10 15 Other features of the invention reside in the construction and arrangement of parts herein-after described and particularly pointed out in the appended claims.

In the accompanying drawing:

20 Figure 1 is a side elevation of the spinning ring and traveler embodying my invention, the same being shown in operative association with the traverse bar and bobbin. Figure 2 is an enlarged top plan view of the ring and traveler. Figure 3 is an enlarged cross section taken on line 3—3, Figure 2. Figure 4 is a fragmentary cross section of a modified form of the ring. Figure 5 is a fragmentary detached view of the coiled wire lubricating wick.

25 30 Similar characters of reference indicate corresponding parts through the several views.

In spinning machines of the character to which my invention is particularly applicable, the threads are delivered by feed rolls (not shown) 35 to a take-up spool 10 and traversing the same is the usual vertically-reciprocating bar 11. Mounted on this bar and surrounding the take-up spool is a supporting member or holder 12 of substantially ring-like form and which is aligned with an opening 13 formed in the bar. Applied to this 40 holder is the spinning or traverse ring 14 upon which the traveler 15 is adapted to be revolved.

Rising from the outer side of the holder body 45 50 55 12 is an annular flange 16 whose top edge 17 forms a seat or shoulder upon which the spinning ring rests, this holder also having a plurality of upstanding radial lugs 18 rising above the flange 16 and against which the outer side of the ring is adapted to bear to retain it in its proper axial position in the holder. The spinning ring 14 is detachably held in a level position within the holder by means of a clamping member which may be in the form of a split ring 19 detachably fitted in notches 20 formed in the holder-lugs 18 and in bearing contact with the top side

of the adjoining portion of the ring, as shown in Figure 3. The lower or base portion of the ring 14 is preferably channel-shaped in cross section to provide an outer or seating flange 21 and an inner or traveler-engaging flange 22, the latter having its lower edge spaced above the base portion of the holder 12.

The upper or main bearing portion of the ring 14 on which the traveler runs is preferably of the cross-section shown in Figure 3, wherein a lower bearing face 23 and an adjoining upper bearing face 24 are provided, the former being flared downwardly and outwardly or frusto-conical in shape and intersecting the contiguous, substantially upright inner bearing face of the ring-flange 22. The upper bearing face 24 is flared upwardly and outwardly from its point of intersection with the companion lower bearing face 23 and terminates at the upper rim-wall of the ring. Formed in the lower bearing face 23 of the ring is an annular lubricant-receiving groove or channel 25 having a charging port 26 leading thereto from the exterior of the ring. Removably seated in this channel is a wick 27 preferably made of coiled wire which by capillary action distributes the lubricant about the ring to effectually lubricate the traveler during operation.

The traveler 14 is made from a single piece of wire and shaped in the manner shown in Figure 3, including an upper inclined bearing leg 30 35 40 45 28 which bears against the upper inclined bearing face 24, a downwardly and outwardly inclined bearing leg 29 which bears against the companion lower bearing face 23 and a pendant leg 30 which is adapted to engage the inner face of the channel-flange 22. The upper bearing leg 28 terminates in a hook-like portion 31 which loosely embraces the top rim of the ring while the pendant traveler-leg terminates in a like hook-like portion 32 which fits freely about the ring-flange 22 and extends into the adjoining channel-way of the ring. At the junction of the bearing legs 28, 29 there is provided a thread-engaging loop 33 which spans the inner portion of the upper bearing face 24.

45 50 55 It will be noted that the ring-bearing faces 23, 24 are at substantially right angles to each other as are the traveler legs 28, 29 and that the thread-engaging loop 33 is at the lowest point of the bearing leg 28, which arrangement effectually eliminates the buzzing sound incident to the spinning of the threads. During the normal running operation of the traveler, its contact with the ring is along the under or oblique bearing face 23, the bearing legs 28 and 30 together with the end 55

loops 31, 32 permitting a limited sliding in and out movement of the contacting bearing leg 29 on the companion ring-bearing face 23. The latter is effectually lubricated by the coiled wick 27 and in this connection the opening in the coil serves as a conduit or manifold to uniformly distribute the lubricant about the entire bearing face of the ring.

In the modified form of the ring shown in Figure 4, the same is made of two pieces consisting of an outer section 34 and a concentrically-disposed inner section 35 to provide a channeled base portion and a rim-like portion having bearing faces similar to those in the previously described construction. The opposing contiguous faces of the upper portions of these ring-sections are shaped to provide a lubricant-channel 36 in which a wick 37 may be fitted.

I claim as my invention:

1. A device of the character described, comprising a spinning ring for travelers having a downwardly-opening channeled base portion providing an outer supporting flange and an inner traveler-engaging flange having an inner, substantially upright bearing face thereon, and having an upper portion including bearing faces disposed at substantially right angles to each other to provide an upper outwardly-inclined bearing face and a lower downwardly and outwardly inclined bearing face intersecting the upper end of the inner face of said traveler-engaging flange.

2. A device of the character described, comprising a spinning ring for travelers having a downwardly-opening channeled base portion providing an outer supporting flange and an inner traveler-engaging flange having an inner, substantially upright bearing face thereon, and having an upper rim-like traveler-engaging portion providing an upwardly and outwardly inclined top bearing face and an adjoining downwardly and outwardly inclined lower bearing face, the latter intersecting the adjoining upper end of the inner face of said traveler-engaging flange, and a traveler shaped to the contour of said ring-faces and terminating in oppositely bent ends engaging the inner flange of said base portion and said rim-like portion, respectively.

3. A traveler for spinning machines, comprising a wire member having adjoining upper and lower bearing legs disposed at substantially right

angles to each other with the upper leg inclined upwardly and outwardly and with the lower leg inclined downwardly and outwardly, a substantially upright bearing leg depending from the lower end of said lower leg, and oppositely bent hook-like portions provided at the terminal ends of said upper leg and said upright leg, the inner end of the upper leg having a thread-engaging loop therein.

4. A traveler for spinning machines, comprising an upper bearing leg, a lower bearing leg extending outwardly and downwardly from the inner edge of the said upper bearing leg in substantially oblique relation thereto, a pendant leg depending from the lower end of said lower bearing leg and terminating in a substantially hook-shaped portion.

5. A spinning ring for a traveler having a traveler-engaging bearing face containing a lubricant channel, and a wick consisting of a coiled wire fitted in said channel.

6. A device of the character described, comprising a spinning ring for a traveler having a traveler-engaging bearing face thereon containing an annular groove, and a metallic wick fitted in said groove and including a spirally-wound tubular member forming a lubricant receiving chamber from which the lubricant is distributed by capillary action to the surface of the windings of said member.

7. A device of the character described, comprising a spinning ring for travelers having a downwardly-opening channeled base portion providing an outer supporting flange and an inner traveler-engaging flange having an inner substantially upright bearing face thereon, and having an upper portion including bearing faces disposed at substantially right angles to each other to provide an upper outwardly-inclined bearing face and a lower downwardly and outwardly inclined bearing face intersecting the upper end of the inner face of said traveler-engaging flange, said lower outwardly inclined bearing face having an annular groove therein, and a lubricant feed element removably fitted in said groove and consisting of a coil spring whose bore constitutes a manifold for receiving the lubricant and whose windings serve by capillary action to distribute the lubricant about said bearing face.
